UNITED STATES PATENT OFFICE

JAMES W. HOLLADAY, OF PLAINVIEW, TEXAS

HYDRAULIC RAM OR PUMP

Application filed May 24, 1930. Serial No. 455,424.

This invention aims to provide a hydraulic ram or pump which will operate with a minimum amount of power and prove efficient and capable of withstanding long-continued use, 5 novel means being provided for producing relative movement between certain constituent parts of the device, to raise the water or other liquid with a ram-like action.

It is within the province of the disclosure 10 to improve generally and to enhance the utility of devices of that type to which the present invention appertains.

With the above and other objects in view, 15 which will appear as the description proceeds, the invention resides in the combination and arrangement of parts and in the details of construction hereinafter described and claimed, it being understood that changes may be made in the precise embodiment of 20 the invention herein disclosed, within the scope of what is claimed, without departing from the spirit of the invention.

In the accompanying drawings:

Figure 1 shows in longitudinal section, a 25 device constructed in accordance with the invention; and

Figure 2 is an elevation wherein parts are 30 in section, portions being broken away in Figures 2 and 1.

The numeral 1 marks a well casing, the 35 constituent members of which are held together by a coupling 2. A ring 3 is threaded in the casing 1, as shown at 4, and has a tapered opening 5 in which is removably seated a tapered valve seat 6, the seat 6 being threaded at 7 into a barrel 8. A ball valve 9 cooperates with the seat 6, and upward movement of the ball valve 9 is limited by a cross pin 10 mounted in the barrel 8. The 40 barrel 8 has an enlarged upper portion 11 forming a shoulder 12, and receiving a packing 14 held in place by a nut 15, a gland thus being formed, in which a hollow piston 16 is mounted for sliding movement, the hollow piston extending downwardly into the barrel 8. In the lower end of the piston 16 there is 45 a seat 41 cooperating with a check valve 40, which may be a ball, upward movement of the ball valve 40 being limited by a stop pin 42 in the piston 16.

A spider 17 is threaded in the upper end of the piston 16 and is secured to a connection 18, in the form of a rod, the upper end of the rod or connection 18 being pivoted at 19 to a pitman 20 which is pivoted at 21 to a crank disc 22, the hub 23 of which is secured at 24 to a shaft 25 journaled in the casing 1 and in a bearing 26 on the casing.

Immediately below the pivot element 19 is 55 disposed an abutment 27 on the connection or rod 18. The numeral 28 designates a float or upper member, provided with a packing 43 adapted to rest on the upper end of the hollow piston 16, although the packing 43 might be 60 mounted on the upper end of the hollow piston 16, if desired. The float or upper member 28 constitutes a closure for the upper end of the hollow piston 16. The space between the casing 1 and the upper member 28 is 65 closed by an annular packing 29 on the upper member 28, and the space between the casing 1 and the barrel 8 is closed by a packing 30 on the barrel. The casing 1 has an outlet 31 70 disposed between the packings 29 and 30 and near to the packing 30.

A tube 32 is mounted at its ends in the 75 end of the float 28. There is a closure plug 33 in the lower end of the tube 32, and there is a plug 34 in the upper end of the tube, these plugs 33 and 34 constituting guides 80 through which the connection or rod 18 passes. A compression spring 35 surrounds the upper portion of the rod 18. The upper end of the spring 35 abuts against the member 27 and the lower end of the spring engages 85 the plug 34. The compression spring 35 serves to maintain the upper member 28 seated yieldably on the upper end of the hollow piston 16, as shown in Figure 1 of the drawings.

The crank disc 22 has a projection 44 90 adapted to engage the upper portion of a yoke 37 mounted on the upper end of the member 28. The ring 38 is slidably mounted on the barrel 8 and is connected by straps 39 with the piston 16.

The piston 16 is raised by the rod 18, the pitman 20, the crank disc 22 and the shaft 25. The upper member 28 is supported on the piston 16 and moves upwardly along with 95 100

the piston throughout the major portion of the up-stroke of the piston. As the piston 16 moves upwardly, the valve 9 opens and liquid is sucked into the lower end of the barrel 8 between the valves 9 and 40, the space within the piston 16, and the space within the casing 1 between the packings 29 and 30 being filled with liquid, the outlet 31 being connected to a pipe line (not shown) so that the liquid in the casing 1 between the packings 29 and 30 does not drain away through the outlet 31 at this stage of the operation. Just before the piston 16 arrives at the limit of its up-stroke, and when the parts are in the position shown in Figure 1, the pin 44 on the crank disc 22 engages the yoke 37 and raises the upper member 28 with respect to the piston 16, so that there is a space 45 between the lower end of the member 28 and the upper end of the piston 16. This upward movement of the member 28 sucks an additional amount of liquid into the upper part of the hollow piston 16, past the valve 40, it being recalled that the piston 16 is full of liquid, and that the space between the rings 29 and 30 is full of liquid, and it being understood that the outlet 31 is controlled by the usual backwardly-closing check valve (not shown) common in pump installations and forming no part of the present invention.

As the pin 44 moves clockwise in Figure 1, it passes a vertical plane passing through the axis of the shaft 25, and then the spring 35 reacts to carry the member 28 down on top of the piston 16 and a portion of the liquid in the casing 1 between the packings 29 and 30 is forced with a ram-like effect through the outlet 31. The piston 16 and the member 28 now move down together and liquid in the barrel 8 below the valve 40 is forced upwardly into the piston 16 past the valve 40. Since liquid is caused to enter the piston 16 by the operation last-mentioned, it is obvious that some provision must be made for displacing the liquid that is already in the piston. This is accomplished because the member 28 can have a slight upward movement at this stage of the operation, the spring 35 yielding, and the liquid in the piston 16 finding its way out into the casing 1 between the packings 29 and 30.

When it is desired to pull the barrel 8 out of the well, this can be done by raising the piston 16, the ring 38 engaging beneath the shoulder 12 on the barrel.

Having thus described the invention, what is claimed is:

In a device of the class described, a hollow piston having a downwardly-closing check valve at its lower end, a crank, means for supporting the crank for rotation, a connection joined to the piston, a pitman pivoted to the connection and to the crank, and upper member slidably on the connection and forming a closure for the upper end of the piston,

spring means for seating the upper member on the piston to effect a closure of the piston, as aforesaid, and a projection on the crank, which engages the yoke, throughout a portion of the rotation of the crank, to space the upper member from the piston and then release the upper member for movement to closed position with respect to the piston, responsive to the springs means.

In testimony that I claim the foregoing as my own, I have hereto affixed my signature.

JAMES W. HOLLADAY.
